UNITED STATES PATENT OFFICE

FRANCIS R. MEGINNISS, OF ALBANY, NEW YORK

DESIGN FOR A COMBINATION READING TABLE AND LAMP

Application filed August 1, 1929. Serial No. 32,260. Term of patent 7 years.

To all whom it may concern:

Be it known that I, FRANCIS R. MEGINNISS, a citizen of the United States, residing at Albany, in the county of Albany and State of New York, have invented a new, original, and ornamental Design for Combination Reading Table and Lamp of which the following is a specification, reference being had to the accompanying drawing, forming a part thereof.

The figure is a perspective view of the combination reading table and lamp, showing my new design.

I claim:

The ornamental design for a combination reading table and lamp, as shown.

FRANCIS R. MEGINNISS.
